UNITED STATES PATENT OFFICE.

LEO LINDBERG, OF COLUMBUS, OHIO.

CLOSET-TANK.

No. 907,384.

Specification of Letters Patent. Patented Dec. 22, 1908.

Application filed October 23, 1907. Serial No. 398,701.

To all whom it may concern:

Be it known that I, LEO LINDBERG, citizen of the United States, residing at Columbus, in the county of Franklin and State of Ohio, have invented certain new and useful Improvements in Closet-Tanks, of which the following is a specification.

My invention relates to the improvement of closet tanks of that class which are used as reservoirs for flushing purposes and the objects of my invention are to provide a tank of this character which is constructed of metal and at the same time obviate the objections heretofore existing to the production of all metal tanks, these objections consisting of expense of construction, tendency of the inner casing to sweat, excessive weight etc. These objects I accomplish in the manner illustrated in the accompanying drawing, in which—

Figure 1 is a sectional view on line $x-x$ of Fig. 2, Fig. 2 is a side elevation of the tank with the outer casing removed and showing for the sake of clearness a portion of the inner casing broken away, and, Fig. 3 is a central vertical section of the tank.

Similar numerals refer to similar parts throughout the several views.

In carrying out my invention, I employ an upright tank or inner casing 1 of metal or other suitable waterproof material, this casing being as shown formed with closed sides and bottom and mounted upon a base plate 2 which may be of wood, if desired.

3 represents an external casing which receives the internal casing and has its forward side and ends arranged at a distance from, but parallel with the forward side and ends of the inner casing. As shown in the drawing, the ends of this external casing are provided with inturned extensions 3^a which overlap the end portions of the internal casing 1. The space 3^b which lies between the forward side and ends of the external casing and internal casing, is closed at its upper end as shown in Fig. 3.

4 represents a sheet of corrugated or crimped metal which as indicated in the drawing, is arranged vertically within the

space 3^b between the inner and outer tank 50 casings, this metallic filling having its projecting portions alternately bearing against the outer surface of the tank casing 1 and the inner surface of the casing 3. It will be observed that the corrugated or crimped metal 55 plate 4, is extended across the back of the inner casing, thereby strengthening the four walls of said casing.

The bracing or strengthening quality of corrugated metal is well known and in the present case, it will be observed that the corrugated sheet 4 not only serves the purpose of forming a strong and durable bracing between the walls of the two casings, but that it forms a comparatively light partial filling 65 for the space between the walls of the two casings, which is of a material not easily affected by dampness or moisture.

It will be observed that if the flues or channels formed by the corrugations of the sheet 70 4 are left open, the air will be free to enter these openings and will to some extent absorb moisture which may tend to collect on the outer surface of the inner casing. In order to insure this absorption, however, of 75 moisture, I may fill the said corrugation channels with suitable absorbent material which will preferably be a non-conductor of heat, such for instance as mineral wool, asbestos or similar material 5.

By referring to Fig. 3, it will be seen that the bottom 2 is secured directly to the lower edge of the corrugated sheet 4, by nails or other fastening devices 10.

It will be understood that a construction 85 such as I have described will result in the production of a closet tank of strong, durable material at a reasonable cost of manufacture.

What I claim is:

1. In a closet tank, the combination with 90 an inner casing adapted to contain water and an external metallic casing, of a corrugated or crimped filling of sheet metal arranged between said internal and external casings, and a filling of absorbent and non-conducting material within the channels formed by the corrugations of said intermediate sheet.
2. In a device of the character described 95

the combination of an inner box-like tank, of
an outer casing spaced from said tank, a
spacing and bracing member formed of
crimped or corrugated sheet metal which lies
5 between the tank and the outer casing, an
absorbent filling material which fills the
spaces between the tank and the outer casing
upon both sides of the corrugated member

and a bottom secured to said corrugated
member and upon which said tank rests. 10

In testimony whereof I affix my signature
in presence of two witnesses.

LEO LINDENBERG.
